UNITED STATES PATENT OFFICE

SAMUEL TILDEN DARE, OF NEW WESTMINSTER, BRITISH COLUMBIA, CANADA

DESIGN FOR A DRINK DISPENSER

Application filed July 18, 1932. Serial No. 44,372. Term of patent 7 years.

To all whom it may concern:

Be it known that I, SAMUEL TILDEN DARE, a subject of the King of Great Britain, and a resident of the city of New Westminster, in the Province of British Columbia, Canada, have invented a new, original, and ornamental Design for a Drink Dispenser, of which the following is a specification, reference being had to the accompanying drawing, forming part thereof.

The figure is a perspective view of a drink dispenser, showing my new design.

The back of the device is a plain panel substantially similar to the front shown in the drawing.

I claim:

The ornamental design for a drink dispenser, as shown and described.

Signed at New Westminster, B. C., this 23d day of June, 1932.

SAMUEL TILDEN DARE.
